UNITED STATES PATENT OFFICE.

GUS W. SWANSON, OF MORGANTOWN, WEST VIRGINIA, ASSIGNOR TO THE UNITED STATES WINDOW GLASS COMPANY, OF MORGANTOWN, WEST VIRGINIA, A CORPORATION OF WEST VIRGINIA.

CAPPING-OFF DEVICE.

Application filed August 8, 1922, Serial No. 580,554. Renewed January 4, 1924.

To all whom it may concern:

Be it known that I, Gus W. Swanson, a citizen of the United States, residing at Morgantown, in the county of Monongalia and State of West Virginia, have invented a new and useful Capping-Off Device, of which the following is a specification.

This invention is a device of the type used in window glass manufacture, for capping-off glass cylinders, and for cutting such cylinders into flattening lengths.

One of the objects of the invention is to provide a device by means of which an electrically heated wire is utilized to impose 15 the cracking tension in capping-off and cutting glass cylinders, in the manufacture of window glass and the like. A further object is to provide a device of the character mentioned, in which the heating wire is so 20 disposed that both ends must be free and disconnected from the current, while said wire is being passed around the cylinder to be operated upon, thereby permitting manipulation of the wire and protecting the 25 operator from danger of electric shocks. A further object is to provide means whereby the wire may be quickly placed in circuit with the heating current, or disconnected therefrom, as occasion may require. A further object is to provide means whereby any slack in the heating wire, after it has been 30 passed around the cylinder, may be readily and quickly taken up, so that the wire will firmly and closely embrace said cylinder, 35 whereby the device is adapted for operation on cylinders of different diameters. A further object is to provide means for anchoring the ends of the heating wire, combined with conductor wires provided with terminals which are movable toward and from 40 the anchored ends of the heating wire, to make and break the circuit to said wire.

The invention will be hereinafter fully set forth and particularly pointed out in the 45 claims.

In the accompanying drawing:—

Figure 1 is a top plan view, parts being shown in section, illustrating a capping off switch constructed in accordance with the invention. Figure 2 is a side elevation, 50 partly in section, showing the parts in capping off position. Figure 3 is a similar view

showing parts in positions assumed after the heating wire has been engaged with the cylinder, but before the slack has been taken up. Figure 4 is an end view.

Referring to the drawing, 10 designates a base of insulating material, preferably of fiber, provided with a longitudinal groove or channel 11, in which is mounted a slide 12. Said slide supports a stationary member 13, to which is pivotally connected a clamp member 14. Said clamp member is held in clamping position by means of a latch 15, pivoted to the member 13 and engaging a pin 16.

The stationary member 13 is provided with longitudinally disposed grooves or seats 17, to receive tubes 18 of insulating material such as fiber, for instance. Said tubes 18 are provided with notches 19, engaging complementary projections 20 on the member 13, whereby relative longitudinal movement of the tubes and the member 13 is prevented.

The heating wire 21 has its ends secured to rod-like conductor members 22, extending through the tubes 18, and provided with reduced portions 23. Said reduced portions are positioned to engage notches 24, in an anchoring piece 25, secured to the base 10, the extremities of said rods 22 being enlarged, as indicated at 26, to form electric contacts.

Secured to the base 10 is a switch 27, which may be of any preferred or desired construction, controlling the passage of current through the conductors 28, which may be connected to a source of electrical energy by any well-known or desired means. The conductors 28 lead to terminals 29, located within a terminal block 30, secured to a support 31, which is slidably mounted in the channel 11 of the base member 10. The support 31 is provided with a spring-catch 32, which engages a notch 33 formed in the slide or support 12, and is positioned to be disengaged by coming in contact with the edge of one of the overhanging plates 34 which retain the slide 12 in place.

In practice, when it is desired to cap a cylinder or to cut the same into flattening lengths, the operator disengages the latch 15, whereupon the clamp member 14 is free

to swing upon its hinge-support and thereby release the tubes 18 and the conductor members 22 located therein. The operator then throws one of the tubes and its enclosed conductor member, around the cylinder and draws it taut, after which both tubes 18 are returned to their seats in the member 13, with the conductor members in engagement with the anchoring member 25. The clamp member 14 is then placed over the tubes 18, and locked in position by means of the latch 15. It will be understood that the parts are now in the positions illustrated in Figure 3, the contacts 26 being out of engagement 15 with the contact terminals 29. The operator now slides the member 13 longitudinally of the base 10, the tubes 18 moving therewith toward the cylinder, thereby taking up the slack in the wire 21 and holding the latter 20 firmly and closely around the cylinder. As the member 13 moves along the base 10, the support 31 and terminal block 30 are moved simultaneously therewith by reason of the connection of the catch 32 with the support 25 12, thereby bringing the terminals 29 into electrical engagement with the extensions 26 of the conductor members 22. By the time 30 that this contact is firmly established, the end of the catch 32 strikes the end of one of the plates 34, causing the catch to be lifted and disengaged from the slide 12, so that the latter with the parts supported 35 thereby, may continue to move toward the cylinder until all of the slack in wire 21 is taken up. After the wire 21 has been closed snugly around the cylinder, the operator turns on the current at the switch 27, whereupon the circuit is closed to the said wire 21, and the latter is heated sufficiently to impose a cracking tension upon the glass. In view of the fact that the outer ends of the tubes 18 must be separated by a slight gap, it will be necessary for the operator to tap the stick gently from time to time so as to 40 cause the wire 21 to travel a short distance in a circumferential direction around the cylinder, in a manner which is well understood in the art.

The advantages of the invention will be 50 readily understood by those skilled in the art to which it belongs. It will be particularly noted that by means of the electrically heated wire, the capping-off and cutting of the glass cylinders is greatly facilitated and 55 accurately accomplished. An important advantage lies in the fact that both ends of the heating wire must be free and disconnected from the current, while the wire is being positioned around the cylinder. This 60 is because the conductor members 22 cannot be removed until the block 30 has been moved away from the ends 26 of said conductor members. Thus the operator is insured against danger of shocks, and at the same 65 time convenient manipulation of the heating

wire is assured. It will also be noted that by providing the sliding adjustment for the insulating sleeves, it is possible to take up all of the slack in the heating wire, so that cylinders of different diameters may be 70 readily operated upon by the same device.

Having thus explained the nature of the invention and described an operative manner of constructing and using the same, although without attempting to set forth all 75 of the forms in which it may be made, or all of the forms of its use, what is claimed is:—

1. A capping-off device comprising a heating wire, conductor members secured to the ends thereof, means for temporarily anchoring 80 said conductor members, conductors having terminals, and means whereby said terminals may be moved into and out of engagement with said conductor members.

2. A capping-off device comprising a heating wire, conductor members secured to the ends thereof, an anchoring member positioned to engage said conductor members, conductors having terminals, and means whereby said terminals may be moved into 90 and out of engagement with said conductor members.

3. A capping-off device comprising a heating wire, conductor members secured to the ends thereof and provided with reduced portions, a relatively fixed anchoring member having notches engaging said reduced portions, conductors having terminals, and means whereby said terminals may be moved 95 into and out of engagement with said conductor members.

4. A capping-off device comprising a heating wire, conductor members secured to the ends thereof, means for temporarily anchoring 105 said conductor members, a movable terminal block, conductors having terminals in said block, and means for moving said block into and out of engagement with said conductor members.

5. A capping-off device comprising a heating wire, conductor members secured to the ends thereof, means for temporarily anchoring 110 said conductor members, a slidably supported provided with a terminal block, relatively fixed conductors having terminals in 115 said block, and means for moving said block into and out of engagement with said conductor members.

6. A capping-off device comprising a heating wire, two conductor members secured to 120 the ends thereof, means for temporarily anchoring said conductor members in parallel relation and close proximity, conductors having terminals, and means whereby said terminals may be moved into and out of engagement with said conductor members.

7. A capping-off device comprising a base, a carrier movably mounted on said base, conductors secured to said base and provided with terminals mounted to move with 130

said carrier, a heating wire having normally free ends positioned to register with said terminals, and means on the base capable of anchoring the ends of said heating wire during movement of the terminals.

8. A capping-off device switch comprising a base, a carrier movably mounted on said base, conductors secured to said base and provided with terminals mounted to move with said carrier, a heating wire, conductor members secured to the ends of said heating wire and positioned to register with said terminals, and means on the base capable of anchoring said conductor members during movement of said terminals.

9. A capping-off device comprising a base, a carrier movably mounted on said base, conductors secured to said base and provided with terminals mounted to move with the carrier, a heating wire having normally free ends positioned to register with said terminals, and an anchoring member secured to said base and positioned to hold the ends of said heating wire against movement during movement of the terminals.

10. A capping-off device comprising a base, a carrier movably mounted on said base, a terminal block slidably mounted on said base, conductors secured to said base and provided with terminals mounted in said block, a heating wire having normally free ends positioned to register with said terminals, and means on the base capable of anchoring the ends of the heating wire during movement of the terminal block.

11. A capping-off device comprising a base, a carrier movably mounted on said base, a terminal block slidably mounted on said base, conductors secured to said base and provided with terminals mounted on said block, a heating wire supported by said carrier and having normally free ends positioned to register with said terminals, a spring-catch carried by the terminal block slide and positioned to engage the carrier, and means on the base capable of temporarily anchoring the ends of the heating wire.

12. A capping-off device comprising a heating wire, conductor members secured to the ends thereof, means for temporarily anchoring said conductor members, conductors having terminals, means whereby said terminals may be moved into and out of engagement with said conductor members, and means for taking up slack in the heating wire after it has been engaged with the cylinder to be operated upon.

13. A capping-off device comprising a heating wire, conductor members secured to the ends thereof, means for temporarily anchoring said conductor members, a movable terminal block, conductors having terminals in said block, means for moving said block into and out of engagement with said conductor members, and means for taking up

slack in the heating wire after it has been engaged with the cylinder to be operated upon.

14. A capping-off device comprising a base, a carrier movably mounted on said base, conductors secured to said base and provided with terminals mounted to move with said carrier, a heating wire having normally free ends positioned to register with said terminals, means on the base capable of anchoring the ends of said heating wire during movement of the terminals, and means for taking up slack in the heating wire after it has been engaged with the cylinder to be operated upon.

15. A capping-off device comprising a heating wire, conductor members secured to the ends thereof, insulating tubes enclosing said conductor members and movable longitudinally with respect thereto, means for temporarily anchoring said conductor members, conductors having terminals, and means whereby said terminals may be moved into and out of engagement with said conductor members.

16. A capping-off device comprising a base, a carrier slidably mounted on said base, sleeves engaged and supported by said carrier, a heating wire, conductor members located within said sleeves and connected to the ends of said wire, conductors secured to said base and provided with movably mounted terminals, and means whereby said terminals may be moved into and out of engagement with said conductor members.

17. A capping-off device comprising a base, a slide mounted on said base and provided with longitudinally disposed seats, insulating tubes complementary to said seats, a pivoted clamp member positioned to maintain said tubes in place on said slide, conductor members located within said sleeves, a heating wire having its ends connected with said conductor members, conductors secured to said base and having movably supported terminals, and means whereby said terminals may be moved into and out of engagement with said conductor members.

18. A capping-off device comprising a base, a carrier slidably supported thereby, a heating wire, insulating tubes enclosing the ends of the heating wire, means for temporarily anchoring the ends of said wire to said base, means for temporarily anchoring the tubes to the slidable member, and conductors having terminals movable toward and from the anchored ends of the heating wire.

19. A capping-off device comprising a base, a carrier slidably supported thereby, a heating wire, insulating tubes enclosing the ends of the heating wire, means for temporarily anchoring the ends of said wire to said base, means for temporarily anchoring the tubes to the slidable member, con-

ductors having terminals movable toward and from the anchored ends of the heating wire, and means providing for relative longitudinal movement of said carrier and 5 said sleeves.

20. A capping-off device comprising a base, an anchoring member rigidly secured thereto, a carrier slidably mounted on said base, insulating tubes engaged by said carrier, conductor members located in said sleeves and positioned to engage said anchor-

ing member, a heating wire having its ends secured to said conductor members, and conductors rigidly connected to said base and provided with terminals movable into 15 and out of engagement with the conductor members while the latter are being held by said anchoring member.

In testimony whereof I have hereunto set my hand.

GUS W. SWANSON.
